US0D1098222S

(12) **United States Design Patent** (10) Patent No.: **US D1,098,222 S**
(45) Date of Patent: ** Oct. 14, 2025

(54) **CARTRIDGE FOR A PLASMA ARC TORCH**

(71) Applicant: **Hypertherm, Inc.**, Hanover, NH (US)

(72) Inventors: **Stephen M. Dunbar**, Lebanon, NH (US); **Christopher Pillsbury**, Lebanon, NH (US); **Micah Roberts**, Lebanon, NH (US); **Devin Karlson**, Thetford Center, VT (US)

(73) Assignee: **Hypertherm, Inc.**, Hanover, NH (US)

(**) Term: **15 Years**

(21) Appl. No.: **29/835,950**

(22) Filed: **Apr. 22, 2022**

(51) LOC (15) Cl. **15-09**

(52) U.S. Cl.

USPC **D15/144**

(58) **Field of Classification Search**

USPC D8/29.1, 30; D15/7-9, 144, 144.1, D15/144.2; D9/723, 724, 726

CPC B23K 9/00; B23K 10/00; B23K 10/02; B23K 28/02; B23K 9/10; B23K 9/06; B23K 9/32; B23K 37/0294

(57) **CLAIM**

The ornamental design for a cartridge for a plasma arc torch as shown and described.

DESCRIPTION

FIG. 1 is a perspective view of a cartridge;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the drawings depict portions of the cartridge for a plasma arc torch that form no part of the claimed design.
